ELASTIC METERING ATTACHMENT FOR
SEWING MACHINES

Joseph Galkin, New York, N. Y.

Application July 29, 1950, Serial No. 176,710

5 Claims. (Cl. 112—214)

1

This invention relates to improvements in sewing machines, and particularly to means for metering or perfectly feeding and stitching an elastic tape to one or more layers of fabric.

It has been the practice heretofore to stretch the elastic tape by pulling it through a spring finger or between two knurled and gear driven rollers to cause friction upon the elastic. However, the rate of stretching varies so that after sewing elastic waistbands for garments, the stitched fabric is gathered unequally by the elastic and the sizes of the waistbands formed are unequal.

An object of this invention is to provide auxiliary feeding means so that the elastic tape will be guided linearly before stitching and attached without any slipping and so as to cause all the elastic waistbands to be identical in size.

Another object of this invention resides in the use and the coactive relationship of a feed roller and a vertically serrated and spring-pressed shoe.

Another object of this invention is to make the feed roller hollow and to place clutch means directly inside the feed roller and to drive the feed roller from the main shaft in the work supporting base and directly at an end face of the puller-feed roller.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of a sewing machine having my invention applied thereto.

Figure 2 is a front elevation of the machine shown in Figure 1.

Figure 3 shows in elevation the front end of the machine, shown in Figures 1 and 2, the work supporting base being shown in cross-section on line 3—3 in Figure 1.

Figure 4 is a top plan view of a vertically serrated shoe.

Figure 5 is an end view of the shoe shown in Figure 4.

Figure 6 is a cross-sectional view taken on line 6—6 in Figure 3.

Figure 7 is a cross-sectional view taken on line 7—7 in Figure 6.

Figure 8 is a cross-sectional view taken on line 8—8 in Figure 6.

2

In the illustrated embodiment of the invention, the numeral 10 indicates the work-supporting base of a sewing machine which comprises the usual standard 11, having an overhanging hollow arm 12 with a head 13 at its free end.

In the head 13 is journaled a needle-bar 14 carrying needles 15. The needle-bar 14 is reciprocated up and down by a needle lever 16 mounted on a pivot shaft 17. The needle lever 16 is connected to the needle-bar 14. A looptaker 18 is oscillated and cooperates with the needles to form stitching. The material worked upon is held down by a presser foot 19 carried by the presser-bar 20. The presser-bar rests on a cloth plate 21 secured to and above the work supporting base 10. A main shaft 22 is suitably journaled in the base portion of the machine and from which the stitch forming and feeding elements are driven, as is well known in the art. The material is moved across the work support by a feed dog 23 which is moved back and forth and up and down in the usual manner.

This invention is directed to mechanism for guiding and feeding an elastic tape 24 to the presser foot 19 and to the feed dog 23. Also for stretching the elastic tape uniformly. This mechanism is identified by the numeral 25 and comprises a right-angular bracket 26 having an upright leg 27 fixed by bolts 28 to the rear base portion 29 of the work-supporting base 10.

The bracket 26 has a horizontal leg 30 which extends forwardly below and to a position in front of the overhanging arm 12.

At the front of the hollow arm 12, the horizontal leg 30 terminates in an upright extension 32 having a clutch shaft 33 fixed therein by screws 34. The bracket extension 32 terminates in a hub 35 having a shoe supporting shaft 36 fixed therein by screws 37. A rod 40 is fixed in the extension 32 intermediate the shafts 33 and 36 by screws 41. The rod 40 is in superposed relation with the clutch shaft 33.

Rotatably mounted on the clutch shaft 33 is a puller-feed roller 42, preferably having a knurled outer surface 43 and positively driven in step-by-step rotation by the main drive shaft 22.

As shown in Figure 3, an eccentric 44 is mounted on the main drive-shaft 22 and is fixed thereto by a screw 45. A strap 46 at one end of a connecting rod 47 is mounted on the eccentric 44. The other end of the connecting rod 47 is pivotally connected to the lower end 48 of an upright lever 49. The lever 49 is fulcrumed on a shaft 50 mounted in a bracket 39 suitably fixed

to the work supporting base 10. The upper end of the lever 49 is pivotally connected at 51 to one end of a horizontal link 52. The other end of the link 52 is pivotally connected at 53 to the lower end of a clutch arm 54.

The arm 54 is slotted to provide adjustability of the pivotal connection between the link 52 and the clutch arm 54 for increasing or decreasing the throw or step-by-step movement of the feed-roller 42 which forms the outer shell of the clutch mechanism 55. This pivotal connection 53 constitutes means for adjusting the movements of the clutch mechanism independently of the movements of the feed dog 23 of the sewing machine.

Mounted on the shaft 36 is a bifurcated member 57 having arms 58 to the lower portion of which a rod 59 is secured by screws 60. A centrally apertured shoe 61 which is preferably of hexagonal cross-section is mounted on the rod 59 and is secured thereon by a screw 62.

As shown in Figure 4, the shoe 61 has triangular teeth 64 all along its length at the rear face 65 where the shoe contacts the knurled outer surface 43 of the feed rollers 42. As shown in Figure 5, the teeth 64 extend the entire vertical distance of one of the sides of the hexagonal outer formation of the shoe. As shown in Figure 5 the rear toothed face 65 is made concave to contact the outer periphery of the feed roller 42. The shoe 61 is pressed by a leaf spring 56 against the roller 42.

Figure 6 is a cross-sectional view taken on line 6—6 in Figure 3 and shows the clutch shaft 33 fixedly held in a bearing portion 66 in the bracket 26 by screws 67. The puller-feed roller 42 is freely rotatably mounted on the shaft 33 and shown in cross-section.

The puller-feed roller 42 has a bore 68 in which an oscillating clutching detent carrier 69 is rotatably mounted. The carrier 69 has a hub 70. Mounted on the hub 70 is a collar 71 on the clutch arm 54. A screw 72 threaded in the collar 71 secures the carrier 69 to the clutch arm 54. (Figure 6.)

As shown in Figure 7, the detent carrier 69 has peripheral cavities 73 in each of which a ball or roller detent 74 and a spring 75 is mounted in a manner as to cause the detent 74 to be wedged between a cam surface 77 in a cavity 73 and the peripheral surface defining the bore 68.

The detent carrier 69 and the detent 74 and spring 75 mounted inside the bore 68 of the feed-roller 42 constitute a friction clutch 80.

Step-by-step rotation of the feed-roller 42 in synchronism with the feed-dog 23 of the sewing machine is effected by the friction clutch 80. The clutch 80 is actuated by the clutch arm 54 and the lever 49 having its lower end in operative engagement with the eccentric 44 on the main shaft 22 of the sewing machine.

In order to prevent reverse movement of the feed-roller 42, I have provided a braking detent carrier 85 freely mounted within a bore 86 in the feed-roller 42, as shown in Figure 8. The braking detent carrier 85 is secured to a disk 87 by a screw 88 and to an arm 89 by a screw 90. The arm 89 is secured to the rod 40 and thus fixed to the bracket 26. (Figure 6.)

The clutch detent carrier 69 and the braking detent carrier 85 are mounted in the feed-roller 42 to work in opposite directions and may be in the form shown and described in Patent No. 1,985,406 issued to Nathan B. Galkin, dated December 25, 1934.

The metering attachment 25, in practice, operates in coacting relation with an improved trimming mechanism 95 comprising a cutting blade 96 fixed to the work supporting base 10 and which lies parallel to the line of stitching and with its cutting edge at the upper level of the work supporting base 10.

A cooperating movable cutting blade 97 is carried by a rocker arm 98 fixed to a shaft 99. The shaft 99 is rockably mounted in bearings 100 in a bracket 101 fixed to the base plate 11 by screws 102.

The rocker arm 98 is oscillated through a link 103 fixed to the shaft 99 and through a strap arm 104 from an eccentric 105 at one end of the main shaft 22.

The movable blade 97 is substantially C-shaped and at its upper portion it coacts with the fixed cutting blade 96 to trim the right-hand edge of the fabric fed by the feed-dog 23 to the needle 15.

In order to positively clear the blades 96 and 97 of the trimmed selvage and prevent clogging of the blades while maintaining a clear upper surface of the work supporting base 10, I provide a main chip guard 106 which is fixed to the bracket 101 by screws 107. The guard 106 has a vertical guard wall 108 extending slightly to the rear of the cutting blades.

The guard 106 has a forwardly and downwardly inclined wall 109 which terminates in a vertical flange 110 at the front face of the base 11.

A further chip guard 112 is secured to the movable blade carrier 100 and slopes laterally and downwardly into the main chip guard 106.

The lowermost portion of the chip guard 106 extends outwardly beyond the base plate 11 and delivers the trimmed selvage clear of the sewing machine.

As shown in Figures 2 and 3, it will be seen that by actuating the shaft 99 at one end thereof by the link 103, that an unobstructed opening 111 is provided in the front portion of the base and in alignment with the main chip guard 106.

The trimmed selvage is thus constrained to move sideways from the presser-foot 19, downwardly over the sloping walls of the chip guard and entirely clear of the forward face of the sewing machine base 10.

The arrangement disclosed makes possible continued operation of the sewing machine because the selvage or chips cannot reach the working parts inside the base 11 and are further kept away from the upper surface of the work supporting base 10 and automatically delivered outside the machine, which was not possible heretofore.

As shown in Figure 3, mechanism for guiding the tape 24 in alignment with the spring-pressed shoe 61 comprises a tensioning guide 120 having a tensioning shoe 121 which is mounted on screws 122 in the head 13. Springs 123 on the screws 122 are tensioned by threaded nuts 124 and hold the shoe 61 against the elastic tape.

A guide pin 125 is carried by an arm 126 secured by a screw 127 to the head 13. A guide finger 128 is secured to the presser foot 19 by a screw 129 and guides the tape 24 to the feed dog 23.

In accordance with the patent statutes I have described and illustrated the preferred embodiment of my invention, but it will be understood that various changes and modifications can be made therein without departing from the spirit of the invention as defined by the appended claims.

I claim:

1. In a sewing machine, a work supporting base, an overhanging arm on said work supporting base, a main shaft in said work supporting base, a main feeding mechanism, auxiliary feeding mechanism including a toothed puller-feed roller having drive clutch and brake mechanism directly therein, a coacting vertically serrated shoe having elongated teeth and being spring-pressed against said roller for gripping and feeding elastic strip material therebetween, said teeth being of considerable length to press a substantial portion of said elastic strip around the peripheral surface of said puller-feed roller, a bracket fixed to said work supporting base, said roller and shoe being supported from said bracket, means for guiding said elastic strip in alignment with said vertical serrations and means for operating said auxiliary feeding mechanism from said main shaft and directly at said puller-feed roller.

2. In a sewing machine, a work supporting base, an overhanging arm on said work supporting base, a main shaft in said work supporting base, a main feeding mechanism, auxiliary feeding mechanism including a puller-feed roller having drive clutch and brake mechanism directly therein, a coacting vertically serrated shoe having elongated teeth and being spring-pressed against said roller for gripping and feeding elastic strip material therebetween, said teeth being of considerable length to press a substantial portion of said elastic strip around the peripheral surface of said puller-feed roller, a bracket fixed to said work supporting base, said roller and shoe being supported from said bracket and entirely clear of said overhanging arm, means for guiding said elastic strip in alignment with said vertical serrations, and means for operating said auxiliary feeding mechanism from said main shaft and directly at an end face of said puller-feed roller.

3. In a sewing machine, a work supporting base, an overhanging arm on said work supporting base, a main shaft and a main feeding mechanism in said work supporting base, auxiliary feeding mechanism including a puller-feed roller having drive clutch and brake mechanism directly therein, a coacting vertically serrated shoe having elongated teeth and being spring-pressed against said roller for gripping and feeding elastic strip material therebetween, said teeth being of considerable length to press a substantial portion of said elastic strip around the peripheral surface of said puller-feed roller, a bracket fixed rearward of said work supporting base and extending forwardly below and to a position in front of said overhanging arm, said roller and shoe being supported from said bracket and entirely clear of said overhanging arm, means above said roller for guiding said elastic strip in alignment

with said vertical serrations, and means for operating said auxiliary feeding mechanism from said main shaft and directly at an end face of said puller-feed roller.

5 4. In a sewing machine, a work supporting base, an overhanging arm on said work supporting base, a main shaft and a main feeding mechanism in said work supporting base, auxiliary feeding mechanism including a puller-feed roller having drive clutch and brake mechanism directly therein, a bracket fixed rearward of said work supporting base and extending forwardly below and to a position in front of said overhanging arm, a vertically serrated shoe having elongated teeth and being spring-pressed against said roller for gripping and feeding elastic strip material therebetween, said roller and shoe being supported from said bracket and entirely clear of said overhanging arm, means above said puller-feed roller for guiding said elastic strip in alignment with the vertical serrations on said shoe, and means for operating said auxiliary feeding mechanism from an eccentric on said main shaft and directly at an end face of said puller-feed roller.

10 5. In a sewing machine, a work supporting base, an overhanging arm on said work supporting base, a main shaft and a main feeding mechanism in said work supporting base, auxiliary feeding mechanism including a hollow puller-feed roller having drive clutch and brake mechanism directly therein, a bracket fixed to the rear wall of said work supporting base and extending forwardly below and to a position in front of said overhanging arm, a vertically serrated shoe having elongated teeth of triangular cross-section, said shoe being spring-pressed against said roller for guiding and feeding elastic strip material therebetween, said teeth being of considerable length to press a substantial portion of said elastic strip around the peripheral surface of said puller-feed roller, said roller and shoe being supported from said bracket and entirely clear of said overhanging arm, a spring-pressed guide mounted on said head, a bifurcated guide mounted on said bracket and above said puller-feed roller for guiding said elastic strip in alignment with the vertical serrations on said shoe, and means for operating said auxiliary feeding mechanism from an eccentric on said main shaft and directly at an end face of said puller-feed roller.

JOSEPH GALKIN.
